ABRASIVE WHEEL CASING

Alton E. Tobey, Santa Cruz, Calif.

Application July 27, 1944, Serial No. 546,821

6 Claims. (Cl. 29—78)

1

The invention relates to a casing or band unit arranged for mounting on a wheel or drum and designed for use in roughing the treads of rubber tires preparatory to retreading or recapping same. More particularly the invention relates to casings of this type employing a set of inner and outer bands arranged for mounting on an expandible rim of the wheel and adapted to support abrading elements in the form of separate prongs extending through perforations in the outer band and provided with heads held between the bands. On this type of casing, because the prongs are formed separate of the bands and become loosened in their mounting after the casing has been used for some time, it becomes necessary from time to time to increase the grip on the prong heads by the bands. This is accomplished by effecting an expansion of the inner band so as to clamp the heads more firmly against the outer band, the expansion of the band being produced by expanding the resilient rim of the wheel on which the casing is usually mounted. In view of this requirement for expansion, the inner band is ordinarily left with disconnected ends and secured to the outer rim at but one point and in a manner permitting freedom of movement of the unsecured portions. However in the casings as heretofore designed, the attachment and form of the inner bands were generally such as not only would afford a too limited expansion of the band but would permit the prongs, when the casing was removed from the wheel, or in the course of shipment of the casings, to become easily released and detached from the bands. It is an object of the present invention to form the bands and secure them together in such manner, that a free and easy expansion of the inner band will be readily permitted when desired and at the same time insuring the retention of the prongs on the casing irrespective of whether the casing is mounted on the supporting wheel.

Another object of the invention is to provide a casing of the character described in which there will be no loose exposed ends of the bands either at the outer or inner peripheries of the casing, and a minimum strain will be imposed on the connected portions of the bands during the use of the casing.

The invention possesses other objects and features of advantage, some of which, with the foregoing, will be set forth in the following description of the preferred forms of the invention which are illustrated in the drawings accompanying and forming part of the specification. It is to be understood, however, that variations in the

2

showing made by the said drawings and description may be adopted within the scope of the invention as set forth in the claims.

Referring to said drawings:

5 Figure 1 is a side view of the band of my invention mounted on a wheel.

Figure 2 is a vertical sectional view of the wheel and casing as shown in Figure 1.

10 Figure 3 is a side view of a portion of the casing on an enlarged scale.

Figure 4 is a vertical sectional view of the portion of the casing shown in Figure 3.

15 As above explained, the casing 5 of my invention is designed for mounting on a wheel or drum 6 such as indicated in Figures 1 and 2. As here shown the wheel is formed of corresponding half sections 7 and 8 arranged to be secured together so as to clamp in position thereon a rim 9 formed of rubber or other resilient material. The sections are mounted on a rotatable shaft 10 and secured in operative relation between a shoulder 12 and one or more nuts 13 having a screw threaded connection with the shaft. The rim 9 is adapted to form a backing for the casing, and the latter may be securely held in position thereon both against relative rotational and axial displacement by drawing the sections together and thereby causing a distention or expansion of the outer periphery of the rim.

20 As will be clear from the drawings the casing is formed with external and internal bands 14 and 15 each of generally cylindrical form and with the band 15 positioned substantially concentrically with band 14. Both bands are formed of resilient sheet metal and the outer band 14 is formed with perforations 16 through which are extended abrading prongs 17 having heads 18 positioned between the bands. Band 14 is designed to provide a ring or annulus of fixed circumference and is preferably formed with outer and inner offset end portions 20 and 21 desirably overlapping one another and secured together by spot welding 22 at the end 23 of the outer portion 20. Band 15 is likewise provided with outer and inner end portions 24 and 25 arranged in overlapping relation and positioned in the outer band with the outer portion 24 arcuately aligned with but spaced from inner portion 21. In distinction to the portions 20 and 21 of band 14, the portions 24 and 25 of band 15 are arranged to be left disconnected from each other but retained inlapping relation, and as a means of holding the band 15 within band 14 and preventing the relative rotational displacement of the bands, the bands

25 are affixed such as by spot welding 27 at a point

of portion 21 outwardly of the end 23 of portion 20, and relative to portion 25 inwardly of the end 23 of portion 21.

The inner portion 25 of the internal band 15 extends considerably beyond the free end of portion 24 so that while the portion 24 is movable circumferentially relative to portion 25, the former will be effectively guided between the portions 20 and 25 in case of such movement and retained in place at all times.

It will now be clear that with the bands as thus formed and designed, when the casing is mounted on the rim 9 the internal band 15 will be substantially free to expand since the only connection between it and the external band is at the welding 27. In this way any tendency toward looseness in the mounting of the prongs after the unit has been in use, will be taken up by the expansion of the band 15 under pressure from rim 9, and should the abrading prongs become loosened beyond the available compensating pressure of the rim, it will be merely necessary to draw the wheel sections more closely together and thereby provide a corresponding expansion of the band 15 with the resultant increased gripping force exerted against the heads between the bands.

It is important to note that inward circumferential movement of portion 24 is limited by portion 21. Likewise, outward circumferential movement of portion 24 is limited since maximum expansion of band 15 will be attained before portion 24 may be withdrawn from between portions 20 and 25. It will thus be clear that accidental release and detachment of the prongs from the unit will be effectively prevented both when the unit is mounted on or removed from the wheel.

I claim:

1. An abrasive wheel casing comprising an inner cylindrical band having overlapping end portions, an outer perforated cylindrical band surrounding said inner band and having overlapping end portions with one portion opposing and in arcuate registration with one of the end portions of the inner band, headed abrasive prongs extending outwardly through said perforations and having their heads held between the bands and weld connections between both overlapping portions of the outer band and substantially between such portions and one of the overlapping portions of the other band.

2. An abrasive wheel casing comprising a cylindrical band having inner and outer overlapping end portions, a perforated cylindrical band surrounding said first band and having overlapping inner and outer end portions with the inner portion thereof in arcuate registration with the outer of said first portions and overlying the inner portion thereof, headed abrasive prongs extending through said perforations and having their heads held between the bands, and means at the overlapping portions of the second band fastening such portions to each other and means adjacent thereto fastening such portions to the inner portion of the first band.

3. An abrasive wheel casing comprising a per-

forated cylindrical band having its end portions secured in radially offset relation, a second band within said first band having inner and outer overlapping end portions the inner of which is affixed to the inwardly disposed portion of the first band adjacent the offset and the outer of which is slidably fitted between and for circumferential movement relative to the inner portion of the second band and the outer portion of the first band, and headed prongs extending through the perforations in said band and having the heads held between the two bands.

4. An abrasive wheel casing adapted for mounting upon a resilient rim and comprising a perforated band having relatively short inner and outer overlapping portions spot welded together along the free edge of the outer portion, an inner band having relatively long inner and outer overlapping portions the outer of which is in arcuate registration with the inner overlapping portion of the first band and adjustably positioned between the outer portion of the first band and the inner portion of the second band, said inner portions being fixed together by spot welding adjacent the free end of the outer portion of the first band, and headed prongs extending through the perforations in the first band with the heads held between the two bands.

5. A casing comprising an outer split band having inward and outward overlapping ends, means permanently connecting said ends together, an inner split band located within the outer band, means permanently connecting one end of said inner band to said inward overlapping end of said outer band adjacent said connecting means first named and at a point spaced inwardly from said end of said inner band whereby said end projects beyond the inward end of said outer band and due to said overlap, in spaced relation to the first band to form a channel, and the other end of said inner band being slidable in said channel.

6. A casing for an abrasive wheel comprising a resilient rim, an outer split band having inward and outward overlapping ends mounted on said rim, means permanently connecting said ends together, an inner split band located within the outer band, means permanently connecting one end of said inner band to said inward overlapping end of said outer band adjacent said connecting means first named and at a point spaced inwardly from said end of said inner band whereby said end projects beyond the inward end of said outer band and due to said overlap, in spaced relation to the first band to form a channel, and the other end of said inner band being slidable in said channel.
